[57] CLAIM

The ornamental design for cosmetic case, as shown and described.

DESCRIPTION

FIG. 1 is a front elevational view of a cosmetic case showing my new design in open condition;

FIG. 2 is a top plan view thereof;

FIG. 3 is a right side elevational view thereof;

FIG. 4 is a rear elevational view thereof;

FIG. 5 is a left side elevational view thereof;

FIG. 6 is a bottom plan view thereof;

FIG. 7 is a front perspective view of the case partially open;

FIG. 8 is a back perspective view thereof;

FIG. 9 is a front perspective view showing my new design in a closed condition; and

FIG. 10 is a back perspective view showing my new design in a closed condition.

The broken line showing of hair curlers in FIGS. 1 and 7 is for illustrative purposes only and forms no part of the claimed design.

FIG. 3

FIG. 2

FIG. 1

FIG. 5

FIG. 4

FIG. 6

FIG. 7

FIG. 8

FIG. 9

FIG. 10
